CLAIM

The ornamental design for a pillow purse, as shown and described.

DESCRIPTION

FIG. 1 is a top front perspective view of a pillow purse showing my new design;

FIG. 2 is a top rear perspective view thereof with a side flap compartment open at the top;

FIG. 3 is a top view thereof illustrated with numbers corresponding to subsequent views and portions of the pillow purse, 4 and 5 reflecting right and left hemispheres of the pillow purse, and 6 reflecting a cutaway view of the pillow purse interior showing the pillow compartment of the side;

FIG. 4 is a cutaway view of the right hemisphere of the pillow purse interior and the flap compartment;

FIG. 5 is a cutaway view of the left hemisphere of the pillow purse interior illustrating a zipper fastener and pillow storage compartment;

FIG. 6 is a side cutaway view of the pillow purse through the pillow purse center on an axis perpendicular to the views of FIGS. 4 and 5, illustrating the pillow storage compartment space and a pillow therein as well as the interior of the flap compartment;

FIG. 7 is a further cutaway view of the left hemisphere of the pillow purse interior view thereof wherein the zipper fastener is only partly engaged and defines an opening to the pillow storage compartment showing a pillow disclosed therein;

FIG. 8 is a front view of the pillow purse;

FIG. 9 is a back view thereof;

FIG. 10 is a left side view thereof; and,

FIG. 11 is a right side view thereof.

The dash-dash broken lines represent stitching and are included in the claimed design. The thick dot-dot broken lines shown in FIG. 7 represent zipper teeth and are included in the claimed design. The dot-dash-dot broken lines used for the areas that represent the pillow shown in FIGS. 6-7 show portions of the article that are not included in the claimed design.
